SCOOP ATTACHMENT FOR INDUSTRIAL TRUCKS

Lloyd L. Quales, Detroit, and John F. Hasler, Dearborn, Mich., assignors to Vickers Incorporated, Detroit, Mich., a corporation of Michigan

Application January 19, 1946, Serial No. 642,237

5 Claims. (Cl. 214—121)

1

This invention relates to material handling trucks, particularly to those of the type provided with forward extending arms adapted for raising materials from the floor to an elevated position.

The invention is more particularly concerned with scoops for handling bulk material such as dirt. The main object of this invention is to provide a scoop of this character which can be readily attached to or detached from the material handling truck within a very short interval of time.

A further object of the proposed device is to provide a bucket or scoop capable of picking up bulk materials from the floor or higher elevations by merely raising the bucket to the desired pick up level and then driving the truck forward, whereby the bucket is forced into the material pile and automatically picks up its load. The loaded bucket is then moved by the truck to its unloading spot.

Another object of my invention is to provide a novel bucket design and method for attaching the bucket to the truck. The scoop design provides a structure whereby the bucket will swing to its normal horizontal loading position when empty and yet will tip up or tilt to its unloading position when loaded and released for dumping.

Further objects and advantages of the present invention will be apparent from the following description, reference being had to the accompanying drawing wherein a preferred form of the present invention is clearly shown.

In the drawing:

Figure 1 is a side elevation of a material handling truck equipped with the proposed device.

Figure 2 is an end elevation of the bucket and means for attaching it to a lift truck.

Figure 3 is a side elevation of the bucket tilted to its unloading position.

Figure 4 is a top plan view of the bucket.

Referring to Figure 1, the truck 10 is provided with a vertical lift column 12 for elevating or lowering the arms or forks 14. The materials bucket 16 is fastened to the forks 14 by a special frame 18. Frame 18 is constructed with engaging members 20 and 22 provided with openings 24 for receiving the fork arms 14.

The bucket 16 and its holding frame 18 are designed so that the scoop will rest on the ground in its correct position for immediate attachment by merely moving the truck 10 forward until the arms 14 have fully entered the openings 24 of engaging members 20 and 22. The frame latch 26 is adapted to catch on the fork structure 28 and be held in engagement by means of spring 28.

2

The bucket 16 is pivoted to the holding frame member 22 by pin 30. The pivot point (30) is slightly forward of the center of gravity of bucket 16. The object for locating said pivot forward of the bucket's center of gravity, is to assure the return of the bucket 16 from a tilted position to its normal horizontal position, after unloading.

Another characteristic of the bucket 16 is the fact that its greater portion of volume is forward of the pivot 30. In fact the forward portion 32 of the bucket 16 is enlarged as compared with the remaining portion to the left of the pivot 30 (Figure 1). As a result of the enlarged portion 32 to the right of pivot 30, the greater weight of material or load tends to tilt the bucket 16 in a clockwise direction for discharging the material load.

When the bucket 16 is tilted to a sufficient angle for the load of material to slide out of the bucket, a tilt stop bar 34 limits further travel. The tilt stop mechanism includes an element 36 attached to the bucket 16 and provided with a slot 38, in which a cross head 40, fastened on the end of bar 34, rides. Bar 34 slides in the collar 42, which is pivoted to holding frame 18. The end of bar 34 is provided with a nut 44 and a compression spring 46 is located on bar 34 between the collar 42 and nut 44. The function of the tilt stop mechanism is illustrated in Figure 3.

As soon as the material load is dumped, the empty bucket 16 will return to its horizontal position by gravitational force as described above. The tilt latch 48 mounted on the holding frame 18 is adapted to engage with the catch 50 on bucket 16 and hold the bucket in its normal loading position as illustrated in Figure 1. In order to release latch 48 the operating arm 52 may be shifted to the left. A cable 54 attached to said operating arm 52 extends to the driver's or operator's seat position whereby the operator can dump the material load by merely pulling on the cable 54.

In operation, with the scoop mechanism set as illustrated in Figure 1, the operator would drive the truck forward until the nose 56 of the bucket 16 is forced into the dirt or material pile. When the bucket 16 has been loaded, the fork arms 14 are then raised on the truck column 12 until clear of the pile and at a suitable elevation for transporting to the unloading point.

When the load has been transferred to its destination, the operator merely pulls on the cable 54 to release the latch 48 from the bucket catch 50. Due to the fact that the larger portion of the load in the bucket 16 is forward of

the pivots 30, the bucket 16 will be tilted or upset to the position shown in Figure 3 at which angle the material load will slide out of the bucket. Since the center of gravity of the bucket is to the left of pivot 30, as soon as the load is dumped, the bucket 16 will return by its own weight to its normal horizontal position where it is again held by latch 48 and catch 50 ready for loading.

While the form of embodiment of the invention as herein disclosed constitutes a preferred form, it is to be understood that other forms might be adopted, all coming within the scope of the claims which follow.

What is claimed is as follows:

1. A dirt scoop for a material handling truck equipped with forward extended lift forks said dirt scoop including a holding frame detachably mounted on said lift forks, a materials bucket pivoted to said holding frame adjacent the ends of the forks at a point on the bucket slightly forward of its center of gravity whereby the empty bucket will return to its loading position by gravity and that portion of the bucket forward of the pivots being of a larger capacity than the rear portion whereby the loaded bucket will dump its load by gravity, and a latch adapted to hold the materials bucket in a horizontal position until released.

2. A dirt scoop for a material handling truck equipped with forward extended lift forks said dirt scoop including a holding frame detachably mounted on said lift forks, a materials bucket pivoted to said holding frame adjacent the ends of the forks at a point on the bucket slightly forward of its center of gravity, whereby the empty bucket will return to its horizontal loading position by gravity, said bucket being approximately twice the length of the lift forks and that portion of said bucket forward of the pivots being of a larger capacity than the rear portion whereby the loaded bucket will dump its load by gravity, and a latch adapted to hold the materials bucket in a horizontal position until released.

3. A dirt scoop for a material handling truck equipped with forward extended lift forks said dirt scoop including a holding frame, means for detachably mounting said frame on the lift forks including openings in said frame adapted to receive said forks as the truck is moved forward, a frame latch for fastening the holding frame to the forks, a materials bucket pivoted to said holding frame adjacent the ends of the forks at a point on the bucket slightly forward of its center of gravity, and a latch adapted to hold the materials bucket in a horizontal position until released.

4. A dirt scoop for a material handling truck equipped with forward extended lift forks said dirt scoop including a holding frame, means for detachably mounting said frame on the lift forks including openings in said frame adapted to receive said forks as the truck is moved forward, a frame latch for fastening the holding frame

5 to the forks, a materials bucket pivoted to said holding frame adjacent the ends of the forks, said bucket being approximately twice the length of the lift forks and that portion of said bucket forward of the pivots being of a larger capacity than the rear portion, and a latch adapted to hold the materials bucket in a horizontal position until released.

10 5. A dirt scoop for a material handling truck equipped with forward extending lift forks, said dirt scoop including a holding frame, openings in said holding frame adapted to receive the lift forks, a materials bucket pivoted to the holding frame adjacent the ends of the lift forks and at a point on the bucket slightly forward of its center of gravity whereby the empty bucket will return to its horizontal loading position by gravity, said bucket being approximately twice the length of the lift forks and that portion of said bucket forward of the pivots being of a larger capacity than the rear portion, whereby the loaded bucket will dump its load by gravity, a resilient stop device formed as an integral part of the bucket and holding frame for limiting the unloading angle of the bucket comprising in combination, a tilt stop element fastened to said bucket, a longitudinal slot in said element, a cross head reciprocably mounted in said slot, a collar pivoted to the holding frame, a bar fastened at one end to said cross head and slidably journaled in said collar, a nut on the collar end of said bar, a compression spring mounted on the bar between the nut and the collar, a frame latch for fastening the holding frame to the forks, a bucket latch for retaining the bucket horizontal on the forks, and means for releasing said bucket catch and dumping the bucket.
